US00D906171S

(12) **United States Design Patent** (10) Patent No.: **US D906,171 S**
Chen et al. (45) Date of Patent: **** Dec. 29, 2020**

(54) **AERIAL VEHICLE**

(71) Applicant: **SZ DJI Technology Co., Ltd.**,
Shenzhen (CN)

(72) Inventors: **Shaojie Chen**, Shenzhen (CN); **Yumian Deng**, Shenzhen (CN)

(73) Assignee: **SZ DJI Technology Co., Ltd.**,
Shenzhen (CN)

(**) Term: **15 Years**

(21) Appl. No.: **29/658,951**

(22) Filed: **Aug. 3, 2018**

Related U.S. Application Data

(63) Continuation of application No. 29/592,589, filed on Jan. 31, 2017, now Pat. No. Des. 852,673, which is a (Continued)

Assistant Examiner — Messina L Smith

(74) *Attorney, Agent, or Firm* — Sterne, Kessler, Goldstein & Fox PLLC.

(57) **CLAIM**

The ornamental design for an aerial vehicle, as shown and described.

DESCRIPTION

FIG. 1 is a top front perspective view of an aerial vehicle showing the claimed design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a top front perspective view of the aerial vehicle of FIG. 1 in an alternate position;

FIG. 9 is a front view thereof;

FIG. 10 is a rear view thereof;

FIG. 11 is a left side view thereof;

FIG. 12 is a right side view thereof;

FIG. 13 is a top view thereof; and,

FIG. 14 is a bottom view thereof.

The dashed broken lines in the figures show portions of the aerial vehicle that form no part of the claimed design.

The shade lines in the figures show contour and not surface ornamentation.

1 Claim, 11 Drawing Sheets

Related U.S. Application Data

continuation of application No. 29/555,483, filed on Feb. 22, 2016, now Pat. No. Des. 814,970.
